UNITED STATES PATENT OFFICE.

WILLIAM F. HANNES, OF OAKLAND, CALIFORNIA.

WIRE FRUIT-JAR FASTENING.

SPECIFICATION forming part of Letters Patent No. 314,332, dated March 24, 1885.

Application filed August 14, 1884. (No model.)

To all whom it may concern:

Be it known that I, WILLIAM F. HANNES, of the city of Oakland, in the county of Alameda and State of California, have invented 5 an Improved Fastening for Covers of Fruit-Jars, of which the following specification is a full, clear, and exact description.

The object of my invention is to provide a cheap, simple, and effective fastening for the 10 covers of fruit-jars and other covers and stoppers; and it consists in certain novel construction and combination of parts for the purpose, as hereinafter described.

Referring to the drawings that accompany 15 and form a part of this specification, Figure 1 is a plan view of a jar-top with my device applied. Fig. 2 is a side elevation of the jar and a section of the cap with my fastener thereon in an open position. Fig. 3 is a side 20 elevation of the jar and top or cap with my fastener applied closing the jar, a part of the rim of the cap or top being broken away to show the application of my fastener.

A represents the upper portion or neck of 25 a wide-mouth bottle or jar, and B the cover or top to cover and seal or tightly close the opening.

Around the neck of the bottle or jar is placed a ring or coil of stout wire, D, to which 30 at opposite sides are attached two wire arms, E E, of suitable length to extend over and across the top of the cover, and also to overlap each other. These wires are attached to the ring D by means of an eye, d, or several 35 turns of the end around the ring wire, and at the outer or free end a hook, C, is formed on each. While thus permanently attached to the ring D, and by this means confined on the

neck of the bottle or jar, these wires are free to be turned up and be brought over from opposite directions diametrically across the cover B; or when the bottle or jar is opened they can be thrown off and yet remain attached for future use.

To fasten and hold the cover in place on the 45 jar, these wires are first brought over across the top of the cover and closely in line with each other, and with their endslapping past each other, and these ends are then fastened and held firmly down by springing the hooked 50 end of one wire under the other wire. The stiff and also springing quality of the wires is then sufficient to keep them hooked and cause them to lie closely against the top of the cover and hold it firmly down upon the bottle or 55 jar.

Having thus fully described my invention, what I claim, and desire to secure by Letters Patent, is—

1. The herein-described fastening for covers 60 of fruit-jars, consisting of the ring D and the overlapping wire arms E E, adapted to extend over the cover from opposite directions, and provided with hooked ends C C, substantially as described.

2. The combination, with a fruit-jar, of the 65 ring D, surrounding the neck, and the attached wire arms E E, permanently connected to the ring D, and having the hooked ends C C, the said wires being of suitable length to extend 70 over the cover of the jar and overlap each other, substantially as described.

WM. F. HANNES. [L. S.]
